UNITED STATES PATENT OFFICE.

MICHEL CARL ZEDERBAUM, JOB FISH, JR., AND LOUIS JOHN KIRCHENBAUER, OF YONKERS, NEW YORK, ASSIGNORS TO OTIS ELEVATOR COMPANY, OF JERSEY CITY, NEW JERSEY, A CORPORATION OF NEW JERSEY.

SWAGING MACHINE.

Application filed September 25, 1920. Serial No. 412,801.

To all whom it may concern:

Be it known that we, MICHEL CARL ZEDERBAUM, JOB FISH, Jr., and LOUIS JOHN KIRCHENBAUER, citizens of the United States, residing in Yonkers, in the county of Westchester and State of New York, have invented a new and useful Improvement in Swaging Machines, of which the following is a specification.

10 Our invention relates to forging or swaging machines and the object of our invention is to provide a machine to form the ends of hollow or solid cylindrical forgings or bars into conical shapes of predetermined measurements by means of the application of several pneumatic hammers, the sectional forming dies, the hammers and dies constituting parts of the machine.

15 The following is a full, clear and exact description of our invention, reference being made to the accompanying drawings of which Figure 1 is a front view of the machine.

Figure 2 is a side view of the machine. Figure 3 is a top view of the machine. Figure 4 is a clear view of the operating and controlling mechanism.

Figure 4^a is a sectional view on line 1—1 in Figure 4.

Figure 5 is a side view of Figure 4 with certain parts broken away.

Figure 6 is a sectional view of the clutch device.

Figure 7 is a top view of the cast iron table.

Figure 7^a is a sectional view on line 3—3 in Figure 7.

Figure 8 is a sectional view of Figure 7.

Figure 9 is a top view of a die.

Figure 10 is a sectional view of Figure 9 showing the shape of the die.

Figure 11 is a sectional view of the table with the die in place, showing also a forging in the die and the shape of the different hammers used with my invention.

Figure 12 is a view of the locating collar and centering bushing.

Figure 13 is a sectional view of Figure 12.

Figures 14, 15 and 16 are different views of the holding fixture.

Figure 17 is a view of a thimble rod after it went through the process of our invention.

Figure 18 is a view of the same thimble rod before it went through the process of our invention.

The machine consists of a heavy cast iron circular table G resting on three substantial cast iron legs, g. The table G supports a vertical column H which holds the center spindle I and carries the actuating mechanism for the rotation and the up and downward motion of the spindle I. In the center of the table G is provided a permanent recess K containing a die L (Fig. 11) which is made up of three segmental sections, and radiating therefrom at 120° angles are held three pneumatic hammers, M, N, and O, which are firmly attached to the table G by means of specially designed clamps P in recesses R (Fig. 7) cast integral with the table G. These three hammers, M, N, and O, are in a horizontal plane, whereas a fourth hammer S is located vertically directly under the center of the die L. The center spindle I, which is provided with a slot i on the center line and on the lower extremity of which is located a holding fixture T for the proper securing of the work, is rotated by means of a worm U and gear device V (Fig. 5) through a frictional clutch W and the downward motion is accomplished by a counterweighted lever X. The upward or return movement of the spindle I, after the completion of the work, is accomplished by a pneumatic cylinder Y. A pulley Z can be belted up to a suitable source of locomotive force and the number of revolutions per minute of the pulley depends upon the purpose for which the machine is used.

For the purpose of illustration the machine as shown on the accompanying drawings is prepared to swage thimble rods as shown in Figure 18 into the shape as shown in Figure 17. Before explaining the operation, I will describe in detail the various parts of our machine, reference being made to Figures 4 to 18.

In the case of swaging thimble rods as used for illustration, the clutch pulley Z should run at about 200 revolutions per

55

60

65

70

80

85

90

95

100

minute. The proper tension on the friction clutch W is obtained by pressing the foot pedal 20 down level with the floor and adjusting the turn buckle 21 until the spindle 5 I revolves. Then give turn buckle about $\frac{1}{4}$ of a turn more. It is advisable not to adjust the clutch W too tightly so that if the thimble rod should stick in the die, the clutch W will slip, thus preventing the 10 thimble rod from twisting in the arch.

Referring to Figures 4, 5, and 6, it will be noticed that the pulley Z is running free on the shaft 23 which is held in place by the three bearings, 24, 25 and 26. The bearings 15 24 and 25 are a part of the vertical column H. Between the bearings 24 and 25 on the shaft 23 is the worm U which meshes with the worm gear V. The bracket 27 is bolted to the column H and carries a bronze sleeve 20 bearing 26 permanently fastened to this bracket with 3 screws to prevent motion. This sleeve bearing has on the portion extending beyond the bracket an external square thread shown in Figure 5. The arm 25 28 is threaded on the inside of its hub portion to match the thread on the outside of the sleeve bearing 26. As the latter is fastened permanently to the bracket 27, it is obvious that when the arm 28 is pulled 30 down it will move the clutch W toward the pulley Z and when the leather disk 29 engages the pulley Z, the shaft 23 will rotate with the pulley Z. The clutch W is keyed to the shaft 23 and the key is held in place 35 in the clutch W by two screws and the key-slot in the shaft 23 is of such a length that the clutch can move horizontally over the shaft 23. Between the pulley Z and the clutch W is a spring 30 which serves to separate the clutch W from the pulley Z when 40 the arm 28 is returned to normal position.

The worm gear V, which is operated by the worm U, turns the center spindle I. In Figure 4 is shown how the worm gear V is 45 held in place while the revolving spindle I can move up or down. The hub of the worm gear V is provided with a square groove into which fit two clips 31 and 32 which are permanently fastened with two 50 screws each to vertical column H. That part of the center spindle I which passes through the worm gear V has a key-slot extending over such length as is intended to slide through the gear V. The center spindle I and the worm gear V are connected together by means of the key 33 which is permanently held in the key-slot of the gear V by means of screws as shown in section in Figure 4^a. The top section of the center 55 spindle I which fits snugly in the head of the column H is provided with grooves *i*' to act as teeth matching the teeth of segment gear 34 which is keyed to the shaft 35 which has a bearing on each side of the 60 column H as shown in Figure 3. On one

end of the shaft 35 is fastened the counterweight arm X. As shown in Figures 1, 2 and 3, the pneumatic cylinder Y is under pressure and as soon as the valve 36 (Fig. 1) is turned to let the air out of the cylinder Y, the counterweight on the arm X will drop down and the gear 34 will consequently cause the center spindle I to drop down. 70

On the bottom of the spindle I is a holding fixture T to hold the thimble rod in place. Different views of the holding fixture T are shown in Figures 14, 15 and 16. The holding fixture T is fastened to the center spindle I with two bolts 37 and 38. 80 It is made of cast iron and inside has a round opening the shape of the shank and arch of the thimble rod as shown in Figure 14. There is an open slot *t* in one side of the spindle I and fixture T to admit the rod to 85 the spindle and fixture. The rod is held in place in said opening by a clamp or driving clip 39 held across the arch of the rod. The clamp has a fork in one end of it and a slot in edge of its sides near the opposite 90 end. See Figure 15. The fork engages a bolt 41 and the slot the bolt 42, Figure 14, to hold the clamp 39 in place while in operating position. When clamp or driving clip 39 is in open position its end near the 95 fork rests on the bolt 42 and its other end is held in place by a supporting member 40 (Fig. 14). The clamp 39 can be easily lifted out of place by the handle 43 fixed in the clamp as on the bolts 41 and 42 are bosses 100 over which the clamp 39 fits snugly as already told. In Figure 14 a thimble rod is shown, in dotted lines, held in the fixture T in position by driving the clip or clamp 39 (see Fig. 14). 105

On the center spindle I is fastened a locating collar J which can be moved up or down the center spindle I by loosening the bolts 44 and 45. This collar is provided with a centering piece 46 which fits in the slot *i* over the stem of the thimble rod and serves to keep the thimble rod in the center of the die L. The centering piece 46 is held in the locating collar by means of the bolts 47. 110

The compressed air is conducted to the machine through the pipe 48. To this pipe 48 is connected the oil pump 49 which has an oil reservoir 50. As often as may be necessary the operator should pump a little oil 115 in the pipe 48 where the oil mixes with the compressed air and lubricates all the air hammers and the cylinder Y. The hammers M, N and O work always at the same time and are controlled by the valve 51 120 which is operated by the foot pedal 20. After the air has passed through the valve 51, it comes into the distributing box 52 where the air is distributed to the hammers M, N and O. The air supply to the air 125 130

hammer S is taken off the continuation of the main supply pipe 48 directly under valve 51 and is controlled by valve 70 (Fig. 3). The distributing box 52 is fastened to the table G. Cylinder Y is also supplied from pipe 48.

Behind each pneumatic hammer is provided an adjusting support 53 which is fastened to the table with two bolts 53'. In 10 the center is a fibre block 54 which is ground to suit the handle of the pneumatic hammers. This fibre block can be pushed forward by the adjusting screw or bolt 55 which has a hand wheel on one end so as to 15 enable the operator to set each hammer accurately. A lock-nut 56 prevents the adjusting bolt from working loose. The hammer head on the bottom hammer can be removed by unscrewing the two bolts of the support 20 53 and the adjusting screw 55 allowing the hammer to drop down a sufficient distance to get at the head to remove it. See Figs. 1, 2, and 3.

The die L (see Figs. 9 and 10) consists 25 of three sections and between the adjacent ends of each two sections is a spring 57. When the sections are placed in the table, they are held in place by a dowel pin 58 on the bottom and plate 59 on the top by 30 screws 1, see Figure 11. When the die L is in place the springs 57 will push the three sections apart and consequently form three slots in the die L, which are for the purpose of 35 allowing the die sections to move in against the object to be forged. These slots correspond with slots 60 in the die seat K (Fig. 7 and Fig. 7^a). These slots are provided for the purpose of automatic expulsion of scale and grit accumulated during the process of 40 swaging.

All the hammers are provided with proper 45 guards 61 for the protection of the hammers. The guards are simply hollow, partly round, cylindrical shaped, open end hoods placed over the hammers with one open end 50 of the hoods near the die as indicated in the drawings, see for instance, Figures 1 and 2. In the case of one of the guards for example the exhaust air from the hammer it protects 55 is allowed to impinge upon or strike the interior surface of the guard or hood and be thereby deflected to pass out of the open end of the guard next to the die and in that way blow the scale or grit from the top of the die L and keep the sight of the work clear (see Fig. 2).

Having described the different parts of the machine, I will now proceed to explain the operation of the same.

This machine should be set up as close as 60 possible to a blacksmith's forge or oil furnace, where the heating of the forgings can be accomplished and no time lost in transferring the hot forgings to the swaging machine. The three side hammers M, N, and O

should be set so that the end of the hammer head is flush with the die when open. The bottom hammer S should be adjusted accurately by means of the adjusting screw 55, so as to prevent the forming of a thin fin 70 around the bottom edge of the swaged thimble rod. The locating collar J on the center spindle carrying the locating or guiding block 46 should be set so that the shank of the thimble rod forging extends about $\frac{3}{4}$ " 75 into same with the arch of the thimble rod fitting into the seat in the holding fixture T (see Fig. 14).

The operator should be provided with heavy leather gauntlet gloves and should be 80 provided with a suitable tool for inserting and lifting out hot forgings into and from the die L. The stub end of a file with wooden handle and with edges relieved to form a shoulder fitting the arch of the thimble rod forging, is sufficient and forms a part 85 of the equipment of each machine.

Before commencing actual swaging the die L should be preheated to avoid cracking, by placing into it a red hot thimble rod 90 forging and repeating this two or three times without operating the hammers, after which the following sequence of operations should be observed. Heat thimble rod forgings to a bright red color, about 1600° F. 95 keeping basket of arch of the rod out of the fire.

Place hot end of forging into die L.

Raise stem of forging to center of spindle I with left hand.

Lift forging up to seat of holding fixture T using the stub end of a file.

Hold stem of forging in position with left hand thumb in slot of spindle I until the spindle has been lowered and the forging is 105 in contact with the die L.

Lower spindle by pressing down with right hand the lever on valve 36, letting the air out of cylinder Y.

Slide clamp or driving clip 39 to the left 110 into position locking the arch of the thimble rod forging into the holding fixture T.

Step on foot pedal 20. This causes the arm 28 to move down and forces the clutch W into engagement with the pulley Z which 115 again causes the center spindle to rotate. At the same time, pressing down the foot pedal 20 causes the three side hammers M, N and O to operate.

Open with left hand the valve 70 which 120 starts the operation of the bottom hammer S.

Release foot pedal 20 after spindle I has made a complete revolution. This stops the revolving of the spindle I as the springs 71, 125 on plate 71', on column H push the arm 28 back to normal position and releases the clutch. At the same time, the operation of the three side hammers is stopped.

Raise spindle I by pushing up the lever 130

on valve 36, with the right hand, admitting air in the cylinder Y, which raises the counterweight arm X, and at the same time shut off, with the left hand, the valve 70 which 5 stops the bottom hammer S.

Slide driving clip 39 to the right and remove the finished thimble rod by inserting stub end of the file under the arch of the rod, using right hand for this purpose, and 10 steady the shank of the forging with the left hand.

It is obvious that forgings of different sizes and shapes can be swaged with this 15 machine and to change the dies and holding fixtures the following should be observed.

Raise the spindle I as high as it will go by operating the lever of valve 36 which 20 controls cylinder Y. Insert a safety pin 73 which will be found attached by a chain to the main frame of the machine (Fig. 1) into the hole 74 (Fig. 2) of the connecting rod 75 near the top of cylinder Y. This will prevent spindle I from dropping in case the air pressure is released accidentally.

25 Remove the holding fixture T and the plate 59 covering the die L.

Block up the foot pedal 20 as this prevents the possibility of accidentally starting the revolving of spindle I or the operation 30 of the hammers M, N and O.

Turn the valve 70 controlling the bottom hammer S to drive up the sections of the die L enough to get hold of them, and they can be removed easily.

35 Take out the lower hammer head to blow out scale or grit and replace with whichever hammer head is needed.

Put the expansion springs 57 into the die sections of whichever die is going to be 40 used and draw the segments together with a standard lathe dog, which will have to be slightly altered so that when used the points of contact will be on the joints of the die sections. A standard lathe dog is merely a 45 ring with set screws in it with their ends inwardly directed. The die sections are assembled together with the springs between the two adjacent ends of the sections and the whole assembly placed in the ring or lathe 50 dog with the free ends of the lathe dog screws slightly altered from their usually pointed shape to a wide surface on their ends to span the joints between the adjacent ends of the sections. The screws are then 55 screwed in against the sections until the adjacent ends of the sections abut each other. After which the die is entered in the holder for the die.

Enter the die in line with the dowel pins 60 58 in the bottom of the die holder K. Remove the lathe dog from around the sections and push the die sections in place in the holder K.

Replace the plate 59 covering the die 65 segments.

Attach suitable holding fixture to the underside of the spindle I and finally open the air supply to the cylinder Y and remove the safety pin.

Having thus described our invention, what 70 we claim as new and desire to secure by Letters Patent is:

1. In a forging machine, a table having a central recess, dies therein, radial recesses in said table, hammers in said recesses, said radial recesses having an opening in line with said central recess, a vertical opening in the bottom of said central recess, a hammer in said opening, the dies being adapted to receive an article to be forged and the hammers to be operated to deliver blows or pressure upon the dies, and article to be forged therein.

2. In a forging machine, a table, a die seat therein, a die seated in the seat, said die seat and die having vertical openings in their bottoms registering with each other, a forging hammer, adapted to strike longitudinally through said openings the article to be forged, and also to strike the die to drive it out of its seat sufficiently to enable it to be gotten hold of to be lifted entirely out of its seat.

3. In a forging machine, a table having a recess or seat for a die, an expandable sectional die seated therein, the sections adapted to receive direct-action hammer blows or impacts, springs between the sections, holes in the bottom of the sections, dowel pins in the bottom of the recess entered in the said holes. 100

4. In a forging machine, a table having a recess or seat therein, adapted to receive or seat an expandable sectional die, dowel pins in the bottom of the recess, a sectional die seated in the recess, a spring between adjacent sections of the die, the sections provided with holes in which the dowel pins enter, and a plate over the top of the sections to retain them in operative position with freedom of movement. 110

5. In a forging machine, a table having a recess or seat therein, and slots in the seat, a sectional die in the recess, springs between the sections pushing them apart from each other to form slots between them, the slots 115 in the die seat and between the sections registering with each other to constitute an exit for scale or grit in the die.

6. In a forging machine, a table, a die therein, a pneumatic hammer, with an exhaust for swaging an article in the die, a guard on the hammer, also of suitable shape and arrangement to conduct the blast of exhaust air to the top of the die and blow the scale or grit therefrom, and thereby to keep 125 the sight of the work clear.

7. In a forging machine, a sectional die with its bottom end open, horizontal pneumatic hammers adapted to deliver blows directly upon the die and a vertical hammer 130

adapted to deliver blows on the article in the die to be forged.

8. In a forging machine, a sectional die, multiple horizontal hammers, radially arranged of the die and adapted to deliver blows simultaneously on opposing sides thereof, and a vertical hammer, adapted to act directly and longitudinally on the blank being forged.
10. 9. In a forging machine, a table, a sectional die having an opening therethrough, adjustable hammers carried by the table, mounted radially of the die and vertically of the opening therethrough, and means to adjust the hammers with respect to the die and the article therein to be forged by them.

10. In a forging machine, a table having a vertical opening therein, a sectional die having an opening in alignment with the opening in the table die, horizontal and vertical, adjustable hammers carried by the table, and means to adjust the hammers to the article to be forged, comprising a support or yoke, secured to the table, and an adjusting screw in the yoke, adapted to set up the hammers.

11. In a forging machine, a horizontal table, provided in its center with a recess or seat, and having vertical openings therethrough, a sectional die seated in the recess, and having a vertical opening registering with the opening in the die seat, multiple adjustable hammers mounted horizontally and vertically to the table, adapted to deliver direct-action pressure on the die and the article in the die to be forged, means to adjust the hammers to set them up to their work, comprising a yoke or support, secured to the table, an adjusting screw in the yoke, and hand wheel to turn it, and a fibre block between the handle of the hammer and the adjusting screw.

12. In a swaging machine, a sectional die, multiple horizontal and vertical pneumatic hammers, adapted to deliver blows or pressures directly upon the die and the article respectively in the die to be forged, and means to distribute air to the horizontal hammers, comprising an air distribution box and means to control the operation of the hammers.

13. In a forging machine, a sectional die, horizontal and vertical hammers, adapted to act directly on the die and longitudinally of the article in the die, and means to support the article in the die under the blows of the hammers.

14. In a forging machine, a sectional die, horizontal and vertical hammers, adapted to act directly on the die and longitudinally of the article in the die, and a holder for the article, comprising an adjustable and rotatable spindle, and means to adjust and rotate it.

15. In a forging machine, a sectional die, horizontal and vertical hammers, adapted to act directly on the die and longitudinally on the article in the die, and a holder for the article, comprising a vertical column, a bracket thereon, and journal bearings in the column and bracket, a rotatable worm shaft in the bearings, a power pulley free on the shaft and a clutch to connect the pulley and shaft together, a rotatable spindle to hold the article to be forged in the die, and a worm gear on the spindle engaging the worm shaft, thereby rotating the spindle when the clutch is operated to connect the shaft and pulley together.

16. In a forging machine, a die, means to rotate and swage an article in the die, means to set into operation the swaging and rotating means, the means to set into operation the swaging and rotating means being connected together, whereby by one operation the operator of the machine can set both swaging and rotating means into operation.

17. In a forging machine, a sectional die, horizontal and vertical pneumatic hammers, acting directly on the die and the article respectively to be swaged in the die, a rotatable spindle to support the article, means to supply air to operate the hammers and rotate the spindle, the said means being connected together, whereby the one operation by the operator serves to set into operation both the hammers and the rotation of the spindle.

18. In a forging machine, a revolvable work-holding spindle, adapted to turn the article in the forging die, a driving pulley to rotate the spindle, a frictional clutch to connect the pulley with the spindle, a hub adapted to be rotated and also moved laterally to cause the clutch to engage the pulley, a foot pedal to turn the hub, and an adjustable connecting rod between the hub and pedal, whereby the friction between the two parts can be regulated suitably to turn the article in the die, but allow slippage between the pulley and clutch in case the article stick in the die.

19. In a forging machine, a rotatable shaft, a power pulley loose thereon, a frictional clutch, comprising a disk, freely splined on the shaft, an exteriorly threaded fixed sleeve, an arm having a hub threaded on the sleeve, adapted to turn the hub, and thereby move the disk into frictional contact with the pulley, a rotatable spindle to support an article to be forged, and means engaging the spindle and shaft to cause the latter to rotate the former.

20. In a forging machine, a vertical column, a rotatable, vertically adjustable spindle to carry the article to be swaged, means to rotate the spindle, comprising a

driven gear shaft, a gear on the spindle, engaging the gear shaft, and provided with a square groove, two clips fastened to the vertical column, fitted into the said groove, 5 a slot and key-way free connection between the spindle and the worm gear, and means to move the spindle up and down.

21. In a forging machine, a vertical column, a vertically movable spindle, to carry 10 the article to be forged, and provided with gear teeth in its upper end, a segment gear, journalled in the said column, and meshed with the teeth in the spindle, a counter-weight, and a pneumatic cylinder connected 15 to the segment gear, the weight to lower the spindle and the cylinder to raise it.

22. In a forging machine, a vertically adjustable work-holding spindle, a cylinder, a pneumatically operable piston therein, 20 adapted to raise the spindle and allow it to drop, a connection rod between the piston and spindle, a hole in the rod near the top of the cylinder, and a pin, adapted to be fitted in the hole in the rod, and hold 25 the spindle against dropping in case the air pressure under the piston is released.

23. In a forging machine, a spindle to carry the article to be forged, and provided with a slot, a locating collar fastened 30 on the spindle, and carrying a centering piece in the slot, the latter adapted to receive the stem of the article to be forged, and the centering piece adapted to fit over

the stem, to keep the article in the center of the forging die.

24. In a forging machine, a spindle to carry the article to be forged, a fixture secured to one end of the spindle to hold the article in place thereon, the said fixture comprising a perforated and slotted holder, 40 the interior shape of the perforation designed to correspond to the exterior shape of the article carried in the holder, a clamp or clip secured to the holder, across the slot therein, adapted to hold the article in the 45 holder.

25. In a forging machine, a work-holder, comprising a fixture, adapted to receive the work, having a slot therein, and bosses thereon, a clamp designed to fit over the 50 slot, one end of the clamp being forked and the other end being notched, to adapt the same to be fitted on the bosses and removed therefrom to an open position, and a supporting member secured to the holder, and 55 designed to hold the clamp when it is in an open position.

In testimony whereof, we have signed our names to this specification in the presence of two subscribing witnesses.
